[57] CLAIM

The ornamental design for an off road automobile auxiliary headlight boot, as shown and described.

DESCRIPTION

FIG. 1 is a front, left side perspective view of an off road automobile auxiliary headlight boot showing our new design, the headlight and support being shown in broken lines for illustrative purposes only;

FIG. 2 is a top plan view thereof on an enlarged scale; FIG. 3 is a bottom plan view thereof on an enlarged scale;

FIG. 4 is a side elevational view thereof, the opposite side being a mirror image;

FIG. 5 is a front elevational view thereof on an enlarged scale;

FIG. 6 is a rear elevational view thereof on an enlarged scale.

FIG. 1***FIG. 2******FIG. 3******FIG. 4******FIG. 5******FIG. 6***
